Primary Examiner — Susan M Lee(74) Attorney, Agent, or Firm — Klarquist Sparkman, LLP(57) CLAIM

The ornamental design for a pet bowl, as shown and described.

DESCRIPTION

FIG. 1 is a perspective view of the new design for a pet bowl. FIG. 2 is a top plan view of the new design of FIG. 1. FIG. 3 is a front elevational view of the new design of FIG. 1. FIG. 4 is a bottom plan view of the new design of FIG. 1; and, FIG. 5 is a back elevational view of the new design of FIG. 1. In the figures, the thinner solid lines appearing within the boundaries of the pet bowl are shading lines used to indicate the bowl's contoured surfaces. The broken lines in the figures are shown for purposes of illustrating environmental structure and form no part of the claimed design.
